UNITED STATES PATENT OFFICE.

ISAAC H. MILLIKEN, OF ASPINWALL, PENNSYLVANIA, ASSIGNOR TO THE McCONWAY & TORLEY COMPANY, OF PITTSBURGH, PENNSYLVANIA, A CORPORATION OF PENNSYLVANIA.

CAR-COUPING.

1,148,037.

Specification of Letters Patent.

Patented July 27, 1915.

Application filed May 5, 1914. Serial No. 836,409.

To all whom it may concern:

Be it known that I, ISAAC H. MILLIKEN, a citizen of the United States, residing at Aspinwall, in the county of Allegheny, and 5 State of Pennsylvania, have invented certain new and useful Improvements in Car-Couplers; and I do hereby declare the following to be a full, clear, and exact description of the invention, such as will enable 10 others skilled in the art to which it appertains to make and use the same.

My invention relates to the construction of car couplers of the vertical plane type, and more especially to such as are primarily 15 designed for application to locomotive tenders.

The principal objects of the invention are to provide a simple, strong and efficient tender coupler in which the coupler head may 20 be readily adjusted to different heights and may be maintained in each of its several adjusted positions without drooping or sagging.

Generally stated, I accomplish these objects by forming the pocket member, to 25 which the coupler stem is pivoted, with a lower supporting wall, flange or lip which projects outwardly beyond the corresponding upper wall of the pocket member, the 30 pocket for receiving the coupler stem being adapted to also receive and prevent rearward movement of a plurality of shims that are generally adapted to occupy a plurality of positions differing in vertical height and 35 vertical alinement.

In the drawings illustrating my invention, the scope whereof is pointed out in the claims, Figure 1 is a view, partly in elevation and partly in vertical longitudinal section, of a tender coupler embodying my 40 invention. Fig. 2 is a view corresponding to Fig. 1, but illustrating the adjusting shims in a different relation. Fig. 3 is a sectional plan view, taken on the line 3—3, Fig. 1. Fig. 4 is a horizontal section, taken in the 45 plane of the line 4—4, Fig. 2, the coupler being shown in plan; and Fig. 5 is an end elevation of the pocket member, the coupler stem being shown in transverse section and 50 the adjusting shims being arranged as in Figs. 2 and 4.

I will now describe my invention more fully, so that others skilled in the art to which it appertains may apply the same.

55 In the drawings, 1 is the coupler pocket,

2 the coupler and 3 the pivot pin by which the pocket member and coupler are connected.

The recess or pocket in the member 1 for receiving the stem of the coupler 2 is of a vertical dimension sufficient to simultaneously accommodate the stem of the coupler and the number of shims 4 that it is desired to employ. In the present instance two shims are shown, such number having been found sufficient to permit the coupler 2 to have a range of vertical adjustment that is ample for all usual conditions of service.

The upper and lower walls of the coupler pocket, which preferably lie in horizontal planes, are formed by the perforated flange members 5 and 6, respectively, through which the pivot pin 3 passes. The lateral walls of the pocket, which for convenience are made similar, are preferably formed with upper and lower, longitudinally disposed faces 7 and 8, respectively, that are in the same vertical plane, the faces 7 and 8 upon the same side of the pocket being preferably separated by an angularly disposed vertical face 9 which serves to limit the lateral swinging of the coupler 2 in one direction, as will be readily understood. As shown more particularly in Fig. 4, the angularly disposed faces 9 converge inwardly toward the cylindrical inner face 10 of the pocket member 1. At the inner ends of the upper vertical faces 7 are shoulders or stops 11 which constitute means for maintaining the proper longitudinal position of the shims 4 when the latter are arranged above the shank of the coupler 2. At the inner ends of the lower vertical faces 8 are corresponding shoulders or stops 12 which similarly serve to maintain the proper longitudinal position of the shims 4 when the latter are arranged beneath the shank of the coupler. As will be noted, the shoulders or stops 11 and 12 are not in vertical alinement, but are so positioned with respect to each other that the lower stops 12 are somewhat in advance of the upper stops 11 or nearer the mouth of the coupler-receiving pocket. By this relative arrangement of the parallel lateral faces 7 and 8 and the stops 11 and 12 on the interior of the pocket member 1, the shims 4 are firmly supported laterally and are prevented from retreating longitudinally when occupying their upper positions as well as when occupying their

more advanced positions beneath the coupler shank.

The adjusting shims 4, either or both of which may be placed within the pocket of 5 the member 1 above or below the shank of the coupler as occasion may require, are preferably slotted or bifurcated at their inner ends, as indicated at 13, so as to permit them to 10 embrace or straddle the pivot pin 3 both when in their upper, inner positions and when in their lower, forward positions. Each of the shims is likewise provided with shoulders or stops 14 which are adapted to engage the corresponding stops 11 and 12 on the interior 15 of the pocket member 1, and each of said shims is also preferably formed with parallel, longitudinally extending lateral faces 15 which correspond with and are adapted to abut against the upper and lower 20 lateral faces 7 and 8, respectively, of the pocket member 1. The forward edges of the shims 4 are preferably curved so as to permit a long shim to be used and yet allow sufficient clearance to enable the coupler 25 to swing freely upon its pivot pin 3.

In the construction illustrated in the drawings the rear face 16 of the striking bracket of the coupler 2 has been availed of as a means for preventing the forward longitudinal 30 movement of the shims 4 when the latter are arranged above the shank of the coupler. This will be readily understood upon an inspection of Figs. 1, 2 and 3. As a means for preventing the forward longitudinal 35 movement of the shims 4 when placed in their lower positions, a downwardly extending bracket 17 on the under side of the coupler head may be conveniently employed.

40 I claim:

1. The combination of a member having a pocket therein, a coupler, means for attaching the coupler to the pocket member, a shim adapted to be received by the pocket 45 of said pocket member in either of a plurality of positions differing in vertical height and vertical alinement, and means independent of said pocket member for maintaining said shim in said pocket.

50 2. The combination of a member having a pocket therein, a coupler, means for attaching the coupler to the pocket member, a shim adapted to be received by the pocket and to occupy a plurality of positions there- 55 in, and means independent of said pocket member for maintaining said shim in said pocket, said pocket member and shim being provided with engaging means for limiting longitudinal movement of said shim, the 60 shim limiting means of the pocket member being arranged in a plurality of different vertical planes.

65 3. The combination with a coupler, of a member having a pocket therein which is provided with longitudinally extending lat-

eral faces and with stop shoulders which are in a plurality of vertical planes, a shim extending laterally beyond the shank of the coupler on opposite sides thereof and having parallel lateral edges and being adapted to engage said stop shoulders, means for attaching the coupler to the pocket member, and means for maintaining said shim in said pocket, said stop shoulders serving to limit longitudinal movement of the shim in one 70 direction and said coupler being provided with means for preventing longitudinal movement of the shim in the opposite direction.

4. The combination with a member having a pocket therein and upper and lower flanges, the lower flange extending forwardly beyond the upper one, of a coupler, means for attaching the coupler to the pocket member, a shim adapted to be received by said pocket, means on the head of said coupler for maintaining said shim in the upper portion of said pocket, and means on the head of said coupler for maintaining said shim in an advanced position in the 80 lower portion of said pocket.

5. The combination with a member having a pocket therein which is provided with longitudinally extending parallel lateral faces and with angularly extending faces 95 which are interposed between said parallel faces, and which is also provided with stop shoulders which are arranged in a plurality of vertical planes, of a coupler, a pivot pin for attaching said coupler to said pocket 100 member, and a shim adapted to be received by the pocket and to occupy a plurality of positions therein, said shim being slotted to embrace said pivot pin and being provided with shoulders adapted to engage the stop 105 shoulders of said pocket member and being formed with parallel lateral edges.

6. A member for tender couplers employing adjusting shims for varying the height of the coupler head, said member having a 110 pocket adapted to receive a shim in either of a plurality of positions which differ in vertical height and vertical alinement, and being provided with outwardly divergent faces and with parallel longitudinally extending faces above and below the same and being provided with a plurality of means for limiting longitudinal movement of a 115 shim, said limiting means consisting of shoulders formed above and below said divergent faces of the pocket member and being arranged in different vertical planes, and said member also having upper and lower flanges, the lower flange projecting forwardly beyond the upper one.

7. The combination of a member having a pocket therein, a coupler, means for attaching the coupler to the pocket member, a shim adapted to be received by said pocket, and means on the head of said coupler for 125 130

preventing the escape of said shim from the pocket when the parts are in assembled position.

8. The combination of a member having a pocket therein, a shim which is adapted to be assembled in said pocket, a coupler, and means for attaching said coupler to said pocket member, said pocket member operating to limit longitudinal movement of said 10 shim in one direction only and said coupler

being provided with means for preventing the escape of said shim from the pocket when the parts are in assembled position.

In testimony whereof I affix my signature, in the presence of two subscribing witnesses. 15
